ATTORNEY.

UNITED STATES PATENT OFFICE.

LOGAN WILLARD MULFORD, OF PHILADELPHIA, PENNSYLVANIA, ASSIGNOR
OF ONE-HALF TO FRANK L. DONLEVY, OF SAME PLACE.

DESIGN FOR A BICYCLE-SUPPORT.

SPECIFICATION forming part of Design No. 26,000, dated September 8, 1896.

Application filed July 18, 1896. Serial No. 599,744. Term of patent 7 years.

To all whom it may concern:

Be it known that I, LOGAN WILLARD MULFORD, a citizen of the United States, residing in the city and county of Philadelphia, 5 State of Pennsylvania, have invented and produced a new and original Design for a Support for Bicycles, of which the following is a specification, reference being had to the accompanying drawing, forming part thereof.

10 The leading feature of my design for a support for a bicycle is an arm and loop-shaped pieces on the end thereof.

The figure represents a perspective view of a bicycle-support embodying my design.

In the drawing, A designates an arm or shank, and B designates an eye to which the same is joined.

C designates limbs which diverge from the shank A, and D designates loop-shaped pieces or clamps on the outer ends of said limbs. 2c

What I claim is—

The design for a bicycle-support, substantially as described and shown.

LOGAN WILLARD MULFORD.
